THERMIONIC TUBE

Filed July 29, 1930

INVENTOR
CHARLES S. FRANKLIN
BY *W.S. Snover*
ATTORNEY

UNITED STATES PATENT OFFICE

CHARLES SAMUEL FRANKLIN, OF LONDON, ENGLAND, ASSIGNOR TO RADIO CORPORATION OF AMERICA, A CORPORATION OF DELAWARE

THERMIONIC TUBE

Application filed July 29, 1930, Serial No. 471,453, and in Great Britain August 16, 1929.

This invention relates to thermionic tubes or valves, and more particularly to thermionic valves of large power, adapted to generate high frequency alternating current. 5 Such valves consist generally of an oil or water cooled anode, which may form part of the outer case of the valve, a cylindrical grid, and a filament, the latter two electrodes being, in constructions at present in common use, supported by the containing glass case which thus serves the triple purpose of excluding air and supporting and insulating the grid and filament. 10 Large valves constructed in this manner, however, are not as rigid as is desirable, and, due to mechanical weakness an unequal expansion of the glass and metal parts under the influence of heat, the grid, filament, and anode are liable to move relatively to one another, thus altering the electric constants of the valve and rendering its performance unstable. 15 The principal object of the present invention is to provide a valve in which this and similar defects are avoided.

The invention is illustrated in the figure of the accompanying drawing, which shows in schematic section one form of construction in accordance with the said invention. In the figure, A represents the anode, G the grid, F the filament, B the band supporting the grid, and C the glass work at the base of the valve. According to the invention, the band B does not form the whole support for the grid system, the said grid system being provided with additional support at the end remote from the glass work. This additional support is provided by means of an insulator M which carries a cap K serving both to act as a corona shield for the insulator and also to hold the grid system G centrally with respect of the anode, the end of the said grid system being attached as shown to the cap K. The top part of the said cap K is formed with ring or annular corrugations after the manner of the operative member of an aneroid barometer, the arrangement being such that while the said grid system is held centrally with respect to the anode, it is free to a limited

degree to move axially, and deformation due to expansion of heating is prevented. It will be seen that with the construction shown there will be little if any liability for the relative positions of the electrodes to change, and in consequence the electrical characteristics of a valve made as shown in accordance with the invention will remain constant after a long period of life. 55

A further advantage of the arrangement illustrated lies in the fact that risks of breakage in transport are reduced while the construction of very large valves is simplified. 60

Obviously, if desired similar insulated supporting means may be provided in connection with the filament. Insulators suitable for use in carrying out the invention may be made of porcelain, steatite, glass, quartz, or similar material. 65

Although not limited to its application thereto, the invention is particularly advantageous in connection with valves intended to be employed for accurately constant high frequency generation. 70

Having described the nature of my said invention, what I claim is:— 75

1. A thermionic tube having grid and anode electrodes, a press for supporting the grid, additional supporting means for said grid comprising a metal cap formed on one side with corrugations and located centrally within the anode by an insulator carried in the end thereof, the arrangement being such that the cap prevents transverse movement of the grid with respect to the anode while permitting limited longitudinal movement. 80

2. In an electron discharge device, having an evacuated envelope, an electrode mounted therein, and supports for said electrode at each end of the envelope, one of said supports including a yieldable connection comprising a corrugated member. 85

3. In an electron discharge device, having an evacuated envelope, an electrode mounted therein, and supports for said electrode at each end of the envelope, one of said supports including a yieldable connection comprising a transverse member having corrugations. 90

4. In an electron discharge device, having an evacuated envelope, an electrode mounted 100

therein, and supports for said electrode at each end of the envelope, one of said supports including a yieldable connection comprising a transverse member having corrugations and insulated from the electrode.

5. In an electron discharge tube having grid and plate electrodes, means for maintaining a fixed spacial relation between said electrodes in a lateral direction while permitting limited longitudinal movement, comprising an insulating member supported by the plate electrode adjacent to one end of the grid electrode, and a second member carried by said insulating member having a corrugated surface for engaging with the said end of the grid electrode.

6. In an electron discharge tube, anode and grid electrodes, and means for preventing lateral movement of the grid with respect to the anode while permitting limited longitudinal movement, comprising an insulated transverse member interposed between adjacent ends of said electrodes having annular corrugations engaging with and yieldably supporting said grid electrode.

7. In an electron discharge tube wherein the anode is closed at one end and comprises a part of the exhausted envelope, a grid electrode within the anode, and means for yieldably supporting one end of the grid electrode from the closed end of the anode, comprising an insulating member fixedly attached to the closed end of the anode and a yieldable member carried by said insulating member abutting the adjacent end of the grid electrode.

CHARLES SAMUEL FRANKLIN.
